CLAIM

The ornamental design for a dispenser, as shown and described.

DESCRIPTION

FIG. 1 is a top, front and left side perspective view of the dispenser showing our new design;

FIG. 2 is a top, rear and right side perspective view thereof;

FIG. 3 is a back elevation view thereof;

FIG. 4 is a left side elevation view thereof, the opposite side elevational view being a mirror image of the side shown;

FIG. 5 is a front elevation view thereof;

FIG. 6 is a top view thereof; and,

FIG. 7 is a bottom view thereof.

The broken line representing the profile of the bottom end and appearance within the broken line form no part of the claimed design.
